EDWARD H. KURTH, OF PASADENA, CALIFORNIA, ASSIGNOR, BY DIRECT AND MESNE ASSIGNMENTS, TO WESTERN ELECTRIC COMPANY, INCORPORATED, OF NEW YORK, N. Y., A CORPORATION OF NEW YORK

EQUALIZED AMPLIFYING TUBE

Application filed November 13, 1928. Serial No. 319,151.

This invention relates to thermionic amplifying tubes, and is particularly concerned with the provision of a tube of the general class in which the feed-back tendency between the output and input elements is inherently neutralized; or in other words, which is truly unilateral in operation.

As is well known in the art, the capacitive coupling existing between the elements of the ordinary tube, and particularly between the plate and grid, cause the amplifier to be inherently unstable and likely to break into undesirable oscillation, this effect increasing with the efficiency of the oscillation circuit, and also as the circuit is adjusted to higher frequencies.

A number of systems have been devised and practiced to prevent or neutralize such oscillations, among the best and most common of which may be mentioned the system (exemplified in the well known neutrodyne circuit) which involves the feeding back of a small quantity of energy external of the tube, this energy being suitable in amount and phase to neutralize the inherent internal plate to grid feed-back of the three element tube. This energy is ordinarily conducted between selected points of suitable phase relationship in the output and input circuits through a small condenser, the capacity of which is adjustable to control the quantity of energy passed. An amplifying system embodying this principle, however, is not equally well neutralized for all frequencies because of an inherent lack of symmetry in the circuit and to the unavoidable presence of inductance and stray capacity in the feed-back condenser connection, which produce unbalanced electro-magnetic and electro-static coupling effects and a consequent tendency toward oscillation. In other words, the neutralizing feed-back current does not pass over a circuit electrically identical under all conditions with that passing the original feed-back current within the tube. These two

feed-back paths may possibly be made electrically equivalent for the amplification of one frequency, but for the amplification of a band of frequencies only a compromise may be made in this adjustment. It is a well known fact to those familiar with the analytical theory of these circuits, as it is known to anyone who has attempted to adjust them in operation, that they cannot operate perfectly over a wide band of frequencies such, for instance, as is commonly used in broadcast work.

The primary object of the present invention may now be stated to be the provision of an amplifier tube and system which is inherently equalized and unilateral for all frequencies and conditions.

With this preliminary discussion of the problem in mind, I shall proceed to a detailed description of my invention, from which its various advantages and features of improvement will become apparent. For this purpose I refer to the accompanying drawing, in which:

Fig. 1 is a diagrammatic view showing the elements of the amplifier tube in elevation;

Fig. 2 is a diagrammatic plan view of the elements of the tube; and

Fig. 3 is a suitable electrical amplifier circuit for the tube.

It will be understood that the specific form and arrangement of the elements of the amplifier tube now to be described are but illustrative of the invention by way of showing one typical means in which it may be carried out in practice; but that this specific arrangement is not controlling on the broad invention, which may be embodied in any physical form or arrangement having the hereinafter specified electrical constants.

Referring now to the drawing, Figs. 1 and 2 illustrate diagrammatically the elements of the amplifier tube, which will be understood to be mounted within a suitable evacuated enclosure, shown at V in Fig. 2. These ele-

ments comprise a thermionic source or filament F, a pair of anode plates P1 and P2 equally spaced on opposite sides of the filament, and a pair of interlocked grid structures G1 and G2, each surrounding the filament and one of the plates. Each grid provides an inner or plate controlling portion 10 between the filament and one of the plates, and an outer or equalizing portion 11 adjacent the outer face of the other plate. The two grid structures, as well as the two plates, are identical in size and form, and are symmetrically located with respect to the other elements of the tube. The two interlocked grids G1 and G2 provide a common compartment 12 in the center of which the filament F is mounted, the filament being accurately located so that equal and opposite changes in the potentials of the two grids will result in equal and opposite changes in plate potentials. The two plates P1 and P2 are mounted in the two outer compartments 13 and 14 respectively, in such a manner that the four plate-to-grid structure capacities C1, C2, C3 and C4, indicated in Fig. 2, are all equal to one another. Each of these several capacities may be considered as embracing the total capacitive coupling effect existing between a plate and one of the grid structures taken as a whole, including not only the adjacent surface 10 or 11, as the case may be, but also the end portions 15 and the remote portion on the opposite side of the filament. Of course, the capacity existing between the plate and the adjacent surfaces of the grid structure has a far greater effect than does the capacity existing between the plate and the remote portions of the grid structure, which may be entirely negligible for practical purposes.

It will be noted that theoretically the exact equality of capacities will not be achieved by a perfectly central location of each plate in its respective compartment, the best position in the arrangement of Figs. 1 and 2 being found with each plate a little nearer to the inner than to the outer adjacent grid surface. This eccentricity in plate location results from a slight additional capacity due to the curved ends 15 of the outer grid surfaces. If, however, the edges of the plate are not too close to the curved ends 15 of the grid structure, compared with the spacing of the plate and grid surfaces themselves, this eccentricity may be so small as to be negligible for all practical purposes, and the central location of the plate may be used.

It will be apparent that the outer or equalizing portions 11 of the grids need not be pervious to electrons, and therefore need not have the same characteristic grid structure as the plate controlling portions 10; but may take any form convenient for manufacture so long as the equality of capacities is maintained. And further, the end portions

15 of the grid, merely having a connective function, may be changed to any other suitable connection. For instance, as shown in the diagram of Fig. 3, the two grid portions 10 and 11 can be joined by a single conductor 15a that can be arranged in any convenient position. In this case the capacity due to the end portions of the grid is reduced to negligible proportions, and the eccentricity in plate location referred to above is eliminated. The form of helical grid cage, in fact, is only a suggested form for manufacture, and may be varied in form and arrangement at will so long as the specified electro-static relations are maintained.

In order to minimize capacitive and inductive relations between the leads from the elements of the tube, I prefer to bring leads 20 and 21 from the two grid structures out of one end of the enclosure, and to bring the plate leads 22 and 23 and the filament leads 24 and 25 out of the other end. As a matter of fact, the capacitive relation existing between the plate and grid leads from the tube when these leads are brought out in relatively close relation may be utilized in a variational physical embodiment of the invention. In this case the grid leads themselves serve as the equalizing grid portions, and are so balanced with respect to the plate leads as to give the desired capacitive relations for complete equalization.

The actual design of the elements in any specific case will depend upon the characteristics desired in the tube for its particular application, and as the principles for such design are well understood in the art, no description thereof will be herein required.

A circuit suitable for the application of this device in the amplification of radio frequency energy is shown in Fig. 3. The two grids G1 and G2 are connected to the opposite ends of the input impedance, which may comprise a continuous inductive winding 30, paralleled by a variable tuning condenser 31, and grounded at its center point through a filament return lead 32 having a resistance 33 and a C-battery supply 34. The two plates P1 and P2 are connected to the opposite ends of an output winding 35, grounded at its center through a filament return lead 36 to the B battery supply. The filament F is grounded through its heating power source, as will be understood.

The resistance 33, which may be, say, of a few hundred ohms, is provided for the purpose of suppressing oscillations which may develop in the circuits formed by the half-sections of the input inductance 30 and the shunted grid-to-filament capacities of the tube. These oscillations are of a frequency independent of the setting of the tuning condenser, and do not cause squeals or whistles due to heterodyning with the input energy;

but are nevertheless objectionable by reason of loading the tube and decreasing its efficiency as an amplifier. Inclusion of the resistance 33, however, effectively suppresses these oscillations, while not lessening the efficiency of the circuit for the amplification of energy having a frequency for which the input circuit is tuned. This fact is obvious from the consideration that the potential difference developed upon the grids across the input impedance is independent of the value of this resistance; and the two components of the current which may be thought of as flowing through the resistance are equal and opposite and thus cancel one another.

This circuiting arrangement will be recognized to embody the general principles of the conventional push-pull type of amplifier, the general operation of which is understood and will require no detailed description here. The novel characteristics of the system will become apparent from the following considerations. As in the genuine push-pull circuit, the two plates, being at the opposite ends of their circuit impedance, are always 180° out of phase, or in other words the potential of one plate reaches its maximum value as the potential of the other plate reaches its minimum value, and vice versa. It may now be seen that due to the peculiar grid structure, by which each grid is provided with a portion adjacent and in equal electrostatic relation to each of the plates, each grid is always under the balanced electrical influence of the two equally and oppositely charged plates, and can therefore receive energy from or be affected by neither. The consequence of this arrangement and its unique advantage is that no current can flow to either grid as a result of any variation in the potential of the plate, or following a change in the frequency of this variation. Moreover, the arrangement is such that the entire system is perfectly symmetrical, and is therefore truly equalized and unilateral for any possible conditions that may be imposed.

It will be understood that the herein detailed embodiment is to be considered merely as illustrative of and not restrictive on the broader claims appended hereto, for various changes in design and arrangement may be made without departing from the spirit of the invention or from the scope of the said claims.

I claim:

1. A thermionic device comprising, a pair of spaced anode plates, a thermionic source located therebetween, a pair of interlocked grid structures, each surrounding the thermionic source and one of the plates, and the plates to grid capacities all being substantially equal to one another.

2. A thermionic device comprising, a pair of spaced anode plates, a thermionic source

located therebetween, a pair of interlocked grid structures, each surrounding the thermionic source and one of the plates, each providing an equalizing portion adjacent to the outer face of the surrounded plate, and each providing a plate-controlling portion adjacent the inner face of the other plate, and the plate to grid capacity between each plate and each of the grid structures as a whole being equal to one another.

3. A thermionic vacuum tube device comprising, a pair of spaced anodes, a thermionic source located therebetween, and a pair of grid structures comprising interfitting spirals each surrounding the thermionic source and one of the anodes, the anode to grid capacities between the anodes and each of the spiral grid structures being substantially equal to one another.

4. A thermionic device comprising an electrode structure including a cathode, two anodes, and two grids, said grids having overlapping portions forming a central enclosure surrounding said cathode and portions forming outer enclosures, each outer enclosure surrounding one of said anodes.

5. A thermionic device comprising an electrode structure including a cathode, a pair of spaced anodes, and two grids, each of said grids comprising one portion having lateral wires extending completely between said cathode and each of said anodes and another portion having lateral wires extending exteriorly of an anode over an area greater than the surface of the anode.

6. A thermionic device comprising an electrode structure including a cathode, a pair of spaced anodes, and a pair of interfitting grids having grid laterals forming inner partitions between both of said anodes and said cathode and having other grid laterals forming outer partitions beyond the surfaces of said anode.

7. A thermionic device comprising an electrode structure including a cathode, a pair of spaced anodes, and a pair of interfitting grids having grid laterals forming inner partitions between both of said anodes and said cathode and having other grid laterals forming outer partitions beyond the surfaces of said anodes, said outer partitions, anodes and inner partitions being in equal electrostatic relation whereby each grid is under the balanced influence of said anodes.

8. A thermionic device comprising an electrode structure including a cathode, two anodes, and a pair of oval-shaped wire grids arranged to form two outer enclosures of equal area and a common central enclosure of lesser area, said cathode being located in said central enclosure, each of said outer enclosures containing one of said anodes.

9. A thermionic device comprising an electrode structure including a cathode, a pair of spaced anodes, and a pair of oval-shaped

wire grids arranged to form two outer enclosures and a common central enclosure, said cathode being located in said central enclosure, each outer enclosure containing one of said anodes, the grid laterals of said central enclosure being a multiple of the grid laterals of said outer enclosures.

In witness that I claim the foregoing I have hereunto subscribed my name this 29th day of August, 1928.
